UNITED STATES PATENT OFFICE.

EDWARD L. BENSON, OF NEW LONDON, CONNECTICUT.

TERMINAL CONNECTER.

Application filed February 3, 1926. Serial No. 85,673.

This invention relates to connectors, and more particularly to terminal connectors to be removably clamped to storage battery terminals.

5 The objects of the invention are:

First; to provide a connector of the character above identified which shall be adapted to be securely and quickly clamped and unclamped from storage battery terminals 10 of various dimensions without in any way damaging the parts of the connector or disfiguring the exposed or contacting parts of the terminals.

Second; to provide a connector of such a 15 construction in which the conducting or cable wires are easily and properly connected thereto and without interfering with the operations during the clamping and unclamping of the connector to the terminals.

20 Third; to so construct and arrange the parts of the connector so that the terminal connections or clamping element can be positively and quickly dislodged or disengaged from the terminal of the battery without 25 the use of a hammer or hitting action and all operations for the clamping and unclamping of the connector from the terminal are capable of being carried out without 30 danger of short-circuiting the battery.

Fourth; to provide a terminal connector 35 having all the attributes of construction and advantages of operation above pointed out and capable of being manufactured at a minimum of cost and at the same time being possessed of maximum durability.

Fifth; other advantages of construction and operation will appear from the detailed description of the parts and manner of attaching and detaching the connector to be 40 hereinafter more fully described.

The invention consists of structural characteristics and relative arrangements of elements which will be presently more fully disclosed and particularly pointed out in 45 the appended claim.

In the drawings, in which similar reference characters indicate the same parts in the several figures:

Figure 1 is a top plan view of the connector partly broken away, and

Figure 2 is a side view of the connector.

Referring to the drawings, 10 is a split ring having the separated ends 11 and 12 and the interior and opposite concave surfaces 13, the curvatures of which are joined together at their inner or rear ends which

spring from the elongated projection 14 for purposes to be presently described.

Cast integral and extending from the end 11 of split ring 10 is provided a lug 15 having a shoulder 16, as shown, and said lug is cast or bored with an unthreaded opening 17.

The other end 12 of the split ring 10 is also provided with a similar lug 18 provided with a threaded opening 19, and the axes of the unthreaded opening 17 and the threaded opening 19 are so constructed and arranged to be substantially in alinement with each other, as illustrated in Figure 1, and the plane of the shoulder 16 is substantially normal to the axes of said threaded openings 17 and 19.

20 is a bolt having at one end a head 21 and at its other end a threaded section 22, and said bolt is so disposed and arranged that its threaded section or end 22 engages the threaded opening 19 of the lug 18 and the unthreaded or shank portion of the bolt 20 passes loosely and with clearance through the unthreaded opening 17, and its head 21 is adjacent to the outer side of the lug 15 and also in proximity to the shoulder 16 of said lug 15.

The elongated projection 14 on the opposite side of the split ring 10 from that of its separated ends 11 and 12 is provided with an opening or socket 23 extending entirely through and is composed of a cylindrical portion 24 and an outwardly flaring portion 25 which abut at their inner ends to 90 form a shoulder 26.

The manner of securely holding the end of a conductor 27 is accomplished by removing the insulation at the end of the conductor the same distance as the depth of the 95 flaring portion 25 of the opening 23, and insert the end section of the conductor 27 into the opening 23 so that exposed edge 28 of the insulation rests against the shoulder 26 within the opening 23, as clearly shown 100 in Figure 1. After the end of conductor 27 is inserted, as described, the exposed wires 29 within and at the end of the conductor are separated and solder 30 is introduced and made to unite the wires and entirely fill 105 the space between said wires 29 and inner wall of the flaring portion 25 of the opening 23, as is common in this class of inventions and will be readily seen provides a cheap construction for properly securing a 110 conductor to a connector, and not only insures the non-corrosion of the exposed end

of the conductor but at the same time the permanency of the union or attachment between the conductor and connector.

The parts being constructed and arranged, 5 as herein explained, the manner of applying the invention is as follows:

If it is desired to attach the connector to the terminal of a battery, a pair of pliers are made to grip the head 21 of the bolt 20 and 10 said head 21 is turned in the proper direction to give sufficient clearance between the inner edge of the head 21 and the outer edge of the lug 15 to permit the ends 11 and 12 to be sufficiently separated and the opposite 15 concave surfaces 13 to encircle and firmly embrace or fit about the tapered end or cylindrical terminal or post 31, shown in dotted lines. To properly adjust the distance between the concave surfaces 13 and 13 or 20 size of the circular opening of the split ring 10 to receive said post 31, the separated jaws of the pliers are then so operated as to have the inner face of one of the jaws abut against the inner edge of the shoulder 25 16, while the inner face of the other jaw of the pliers abuts or engages the outer side of the head 21, and on closing the jaws of the pliers the lug 15 due to the plane of its shoulder 16 being normal to the coincident 30 axes of the unthreaded opening 17 and bolt 20, said lug 15 will readily move and without frictional engagement with said bolt 20, and the distance between the two lugs 15 and 18 is increased and, hence, the two ends 11 35 and 12 and concave surfaces 13 and 13 are correspondingly separated, as will be readily understood.

After the connector has been properly adjusted and seated on the end of the battery 40 terminal or post 31, the pliers are made to engage the head 21 of the bolt 20 and said head is so turned or rotated as to bring by the cooperation of the threaded end 22 with threaded opening 19 the inner edge of the 45 bolt head 21 against the outer and adjacent surface of the lug 15 and on continuing said operation or turning of the head 21, the lug 15 is forced towards the lug 18 and cause the concave surfaces 13, 13, of the split ring 50 10 to firmly grip the battery terminal or post

31 and rigidly clamp or secure the connector with the battery and its terminal, as will be readily understood.

To release or unclamp the connector from the terminal of the battery, the head 21 of 55 the bolt 20 is turned in the opposite direction from above disclosure and said head will assume the position shown in Figure 1, and should the clamping or concave surfaces 13 and 13 be not entirely released or free 60 from the battery terminal or post 31, the above described adjustment and manipulation of the plier jaws with respect to the head 21 and shoulder 16 can be repeated, said plier jaws are disposed so that the inside of one jaw reacts on the outer side of the head 21 while the inner side of the other jaw reacts against the inner side of the shoulder 16 in order to permit the connector to be quickly and safely removed without injury to the connector or battery terminal. 70

From the foregoing disclosure of the construction and arrangement of the improvement and mode of applying the same, it will be seen that all the objects and advantages 75 recited in the statement of invention have been fully and efficiently carried out, and while I have shown and described my preferred form of the improved connector, many changes will readily suggest themselves without in any way departing from the salient features herein disclosed and embodied in the scope of the claim. 80

What I claim is:

In a battery clamp, a split ring having two 85 lugs extending an equal distance therefrom and substantially parallel to each other and aligned openings in said lugs, one of said lugs having a cut away portion on its free end and on the face thereof nearest to the 90 other lug, said cut away portion being of substantially great depth in two directions, longitudinally and transversely, so that when the two lugs abut each other they present shoulders or abutments of such a size 95 and of such a distance from each other that an implement inserted between said shoulders may force said lugs apart.

In testimony whereof I affix my signature.
EDWARD L. BENSON.
